CLAIM

The ornamental design for a pet locator transmitter, as shown.

DESCRIPTION

FIG. 1 is a front perspective view of the pet locator transmitter of the invention;
 FIG. 2 is a front view in elevation of the pet locator transmitter of FIG. 1;
 FIG. 3 is a top plan view of the pet locator transmitter;
 FIG. 4 is a side view in elevation of the pet locator transmitter as seen from the left hand side of FIG. 2;
 FIG. 5 is a side view in elevation of the pet locator transmitter as seen from the right hand side of FIG. 2;
 FIG. 6 is a back view in elevation of the pet locator transmitter; and,
 FIG. 7 is a bottom plan view of the pet locator transmitter of FIG. 2.
